BEAM COMPASS

Rolf M. Eskil, Phoenix, Ariz.

Application September 13, 1943, Serial No. 502,115

4 Claims.

(Cl. 33—27)

This invention relates to a beam compass or to a device for scribing or drawing arcs of great radius.

An object of the invention is to provide an improved beam compass which is of relatively simple and durable construction and which can be economically manufactured which employs a housing within which a steel tape is normally disposed. The steel tape may be withdrawn from the housing to the desired length and clamped in adjusted position. A centering device is associated with the housing and a scribe or marking device mounted on the free end of the steel tape.

By means of the present construction a sturdy type of beam compass is provided which will not only accurately scribe arcs of great radius, but in addition thereto, arcs may be traced or re-drawn without variation.

Another object of the invention is to provide a beam compass wherein a fine adjustment is possible in addition to the rough adjustment accomplished by the withdrawal of the tape from the housing and the clamping of it in its withdrawn position.

Still another object of the invention is to provide a beam compass wherein the body of the housing and its cover can be conveniently assembled and form a simple and durable guide for the tape and the means for clamping as well as a guide for the adjustable arm that carries the center.

With the foregoing and other objects in view, which will be made manifest in the following detailed description and specifically pointed out in the appended claims, reference is had to the accompanying drawing for an illustrative embodiment of the invention, wherein:

Figure 1 is a view in side elevation of the improved beam compass embodying the present invention;

Fig. 2 is a top plan view of the same;

Fig. 3 is a sectional view taken substantially upon the line 3—3 upon Fig. 1 in the direction indicated; and

Fig. 4 is a view in end elevation of the beam compass or may be regarded as taken upon the line 4—4 upon Fig. 1 in the direction indicated.

Referring to the accompanying drawing wherein similar reference characters designate similar parts throughout, the improved beam compass comprises a housing preferably formed of a block 10 of some cellulose plastic, such as for example, Lucite. This block has parallel sides and a relatively large aperture therethrough within which

is normally disposed a steel tape 11. The steel tape 11 may be of any preferred construction or design but preferably it is of that type of tape that is transversely curved so that when the tape is in withdrawn or extended position the transverse curvature effectively stiffens it to cause the tape to have a truss effect. On the free end of the tape there is secured a block 12 preferably also formed of Lucite which is bifurcated or split as at 13 providing opposed jaws which may be caused to clamp on a scribe or lead 14 on the tightening of a tightening screw or bolt 15.

The bottom of the aperture in the block 10 which houses the tape is substantially tangent to the bottom surface of the block and a U-shaped cover 16 fits over the bottom of the block providing sides for the aperture and a bottom 17 that guides the tape 11 as it is withdrawn. The forward side of the block is split as at 18 and a tightening screw or bolt 19 extends across the sides of the cover 16 through the split portion of the block. Preferably, the cover 16 projects forwardly beyond the sides of the block as indicated at 20 to provide an edge of index against which the graduations on the scale may be read. Similarly, the cover 16 projects rearwardly as at 21 to provide a guide for a resilient arm 22 which preferably is formed integral with the block 10. This arm is connected to or anchored to the block 10 adjacent the upper forward corner thereof as indicated at 23 and extends rearwardly over the top of the block 10 in spaced relation thereto, down adjacent the rear side of the block and provides a rearwardly extending split portion 24 equipped with a tightening bolt or screw 25 so that it may be clamped upon a needle 26 that constitutes a center.

A stud 27 extends through the downwardly extending portion of the arm and into the rear face of the block 10. It is equipped with a nut 28 which can be rotated to spring the arm and thus adjust its position. One or more indices 29 may be formed on the sides of the rearwardly extending portions 21 opposite graduations 30 on the bottom of the arm 22. If desired, a vernier scale may be employed at this locality.

In use, the needle point 26 is used as a center. The tape 11 is withdrawn the desired distance and is clamped in this position by tightening the bolt or screw 19. A fine adjustment is possible by rotating the nut 28. With the beam compass thus set the scribe or lead 14 may be caused to draw the arc of the desired radius. The compass may be adjusted to any radius within the length of the tape which is wound about a transverse

bolt 31 which connects the sides of the cover 16 through the center of the aperture in block 10.

It will be noted that the resilient arm is anchored to the block at a point remote from the center or needle 26 so that adequate spring of the arm is normally inherently in the arm because of its length. This may be supplemented however by interposing a compression spring 32 between the rear sides of the block 10 and the bottom of the arm.

From the above-described construction it will be appreciated that an improved beam compass is provided which is of relatively simple and durable construction and which can be economically manufactured and assembled. A fine adjustment is permissible, the lower end of the arm moving in a substantially straight line direction because of the effective length of the arm from the center 26 to the point of attachment at 23. The cover 16 not only serves to provide sides for the aperture and a guide for the tape but cooperates with the split portion at 18 of the block in clamping the tape in withdrawn position.

In place of a scribe or lead 14 any other marking device, such as a pen, might be employed and any equivalent center means may be substituted for the needle 26.

Various changes may be made in the details of construction without departing from the spirit or scope of the invention as defined by the appended claims.

I claim:

1. A beam compass comprising a body constituting a housing, a steel tape adapted to assume a retracted position within the housing or be withdrawn therefrom, means on the housing for clamping the tape in withdrawn position, a scribe on the tape, a center mounted on the housing for adjustment toward and away from the housing, and means on the housing slidably embracing the sides of the center mounting.

2. A beam compass comprising a body having

a transverse aperture therethrough adapted to accommodate a steel tape, a steel tape disposed therein, said body having an opening in its bottom through which the tape may be withdrawn, a U-shaped cover disposed about the body closing the ends of said aperture and cooperating with the body to define a passage through which the tape may slide as it is withdrawn, a scribe on the end of the tape and an adjustable center on the housing.

3. A beam compass comprising a body having a transverse aperture therethrough adapted to accommodate a steel tape, a steel tape disposed therein, said body having an opening in its bottom through which the tape may be withdrawn, a U-shaped cover disposed about the body closing the ends of said aperture and cooperating with the body to define a passage through which the tape may slide as it is withdrawn, the sides of the cover projecting beyond the body, a resilient arm secured to the body having a portion slidably disposed between the projecting portions of the sides of the cover, means for adjusting the arm toward and away from the body, a scribe on the end of the tape, and a center on said portion of the arm.

4. A beam compass comprising a body having a transverse aperture therethrough adapted to accommodate a steel tape, a steel tape disposed therein, said body having an opening in its bottom through which the tape may be withdrawn, a U-shaped cover disposed about the body closing the ends of said aperture and cooperating with the body to define a passage through which the tape may slide as it is withdrawn, said body being split adjacent the passage, means extending through the body adjacent the split portion thereof for causing the split portion to clamp on the tape in its withdrawn position, a scribe on the end of the tape, and an adjustable center on the housing.

ROLF M. ESKIL.
